(57) **CLAIM**

The ornamental design for a wearable blanket, as shown and described.

DESCRIPTION

FIG. 1 is a top, right facing, perspective view of my new design for a wearable blanket;

FIG. 2 is an elevated facing view thereof;

FIG. 3 is an elevated rear view thereof;

FIG. 4 is a top, plan view thereof;

FIG. 5 is a bottom, plan view thereof;

FIG. 6 is an elevated right side view thereof; and,

FIG. 7 is an elevated left side view thereof.

Dashed lines forming a circle in the upper part of the wearable blanket represent unclaimed subject matter, and form no part of the claimed design. Dashed lines on the outer edge seams, and dashes across the body forming crossing patterns represent stitching that form part of the claimed design.
